UNITED STATES PATENT OFFICE

JOHN A. BOHNSACK, OF CLEVELAND HEIGHTS, OHIO, ASSIGNOR TO THE E. F. HAUSERMAN COMPANY, OF CLEVELAND, OHIO, A CORPORATION OF OHIO

JOINT BETWEEN METALLIC BUILDING UNITS

Application filed September 6, 1927. Serial No. 217,636.

The present improvement relates to joints between metallic building units such as the panel units, or sections involving sheet metal elements where a convenient yet adequate form of assembly is desirable; and it is among the objects of the invention to provide a construction which is advantageous in manufacture and easily installed.

A further object, where the general structure is to be of a type including glass panes, is to reduce the light obstructing area of the pilasters between the panes of glass to a minimum. Other objects and advantages will appear as the description proceeds.

The invention then consists of the features hereinafter described and particularly pointed out in the claims; the following description and the annexed drawings setting forth but a few illustrative embodiments of the various forms in which the principle of the invention may be applied.

In said annexed drawings:—

Figure 1 is a broken perspective view showing a joint in a straight run of partition constructed in accordance with this invention.

Figure 2 shows a section near the floor through the joint shown in Figure 1.

Figure 3 is a section through a joint at a two-way corner.

Figure 4 is a section near the floor through a joint at a two-way corner.

Figure 5 is a section through a joint at a three-way corner.

Figure 6 is a section near the floor through a joint at a three-way corner.

Figure 7 is a section through a joint at a four-way corner.

Figure 8 is a section near the floor through a joint at a four-way corner.

In order that there may be the least possible obstruction to light the joint is made directly between the vertical frames 1 of the adjacent panels, without the interposition of a stud or post. This construction is an advantage also as regards movability, because the complete panel units can be stored, moved and erected completely glazed.

In order to fasten the adjacent panels to each other, one or more pairs of clips 2

are used to clamp the edges of one frame to those of the next by means of a bolt 3. Said clips 2 may conveniently be made of sheet metal embossed at 4 to reinforce same and also to form a pocket to accommodate the head or nut of bolt 3.

The clip 2 as shown has the vertical edges bent over at 5 to provide convenient means for attaching a snap-on post cap 6.

It will be noted that said clips 2 do not clamp against the glass 7 with the attendant dangers, but against the sheet iron margins of the panel frames 1 only.

In order to secure the panel frames 1 against transverse displacement there is fastened to the floor a floor clip 8 which is shaped to fit the panel frames 1 and thereby prevent displacement of units after assembly and also allow the exchange of panels when necessary without disturbing said floor clip.

At a two-way corner, Figures 3 and 4, an inside clip 9 is used in connection with a modified form of clip 10 so that the margins of the panel frames are securely clamped therebetween. A special type of floor clip 11 is also used.

At a three-way corner, Figures 5 and 6, an inside compression clip 12 is also used.

At a four-way corner, Figures 7 and 8, a floor clip 8 is used but no other clips are required owing to the fact that an interlocking type of panel frame 1 is used.

Said panel frame 1 has a vertical member of general channel section, with a panel or glass receiving groove 13 in the web portion thereof and an interlocking groove 14 on one flange thereof. That is such groove 14, in the case of either a two-way, three-way, or four-way corner, is adapted to receive the straight flange 15 that forms the complementary element of the adjacent panel, and is held firmly interlocked therewith in assembled condition of parts. While in a straight-away assembly no such interlocking is required, the same type of panel construction is nevertheless adapted for use therein, as shown in Figure 1, and the panel it thus will be seen is of universal type, fitting all conditions.

Other modes of applying the principle of this invention may be employed instead of that explained, change being made as regards the features herein disclosed, provided the means stated by any of the following claims or the equivalent of such stated means be employed.

I therefore particularly point out and distinctly claim as my invention.

1. In a metallic partition structure, the combination of panel units having framing members of generally channel form with parallel flanges, said panel units being assembled with the parallel flanges in opposed spaced alignment to form a hollow vertical, means to secure said aligned flanges together, said means frictionally engaging said aligned flanges and permitting access to the hollow interior, and resiliently secured means covering over said last named means.

2. In a metallic partition structure, the combination of panel units having framing members of generally channel form with parallel flanges, said panel units being assembled with the parallel flanges in opposed spaced alignment to form a hollow vertical, means for securing said flanges, said means frictionally engaging the flanges and permitting access to the hollow interior, and means in association with said flange-securing means for holding post caps over said flanges.

3. In a metallic partition structure, the combination of panel units presenting sheet metal margins, said panel units being assembled with said margins in oposed spaced alignment to form a vertical, spaced clip members for clamping such margins, a screw-threaded member fastened clear of said margins and holding said clips, and post caps engaging over said clips.

4. In a metallic partition structure, the combination of panel units each presenting two parallel sheet metal margins assembled with such margins in oposed spaced alignment to form a hollow vertical, a clamping member frictionally engaging one side of such margins, another clamping member frictionally engaging an opposite side, a screw-threaded member passing clear of said margins and joining said clamping members, and post caps engaging over said clamping members.

5. In a metallic partition structure, a combination of panel units each presenting two parallel sheet metal margins assembled with such margins in opposed spaced alignment to form a hollow vertical, a clamping member frictionally engaging the outside of such margins, another clamping member engaging the inside, post cap engaging means on at least one of said clamping members, and post caps held thereto.

6. In a metallic partition structure, the combination of panel units presenting paral-

lel sheet metal margins assembled with the margins in opposed spaced alignment to form a hollow vertical, a post cap clip frictionally engaging the exterior of such margins, a clamping member engaging the interior, a screw-threaded member passing clear of such margins and joining said clip and clamping member, a post cap held to said post cap clip, and a floor-attached member for positioning such panel unit assem- 70
75

7. In a metallic partition structure, the combination of removable angularly positioned panel frames presenting outstanding margins, and means on adjacent margins for 80
85 interlocking adjacent panel frames.

8. A panel frame and panel for metallic partition structures, said frame having an edge of channel cross-section with parallel flanges in the general plane of the panel, one 85
such flange being formed with a receiving portion adapted to interlock with the flange of a second similar panel member.

9. A panel frame and panel for metallic partition structures, said frame having an 90
edge of channel cross-section with parallel flanges in the general plane of the panel, one such flange being formed with a groove adapted to interlock with the straight flange of a second similar panel member. 95

10. In partition construction, the combination of two panel frames having end members of generally channel form with outstanding flanges, positioned with such flanges in spaced alignment, and another panel frame having a channel vertical angularly positioned with respect thereto, the web portions of all said verticals being equally spaced from a common vertical center line, and means for securing all said verticals in position. 100
105

11. In partition construction, the combination of two generally channel shaped homologous sheet metal verticals positioned with their flanges in spaced alignment, and another homologous vertical angularly positioned with respect thereto, the web portions of all said verticals being equally spaced from a common vertical center line, 110
115 and means for holding said verticals in position.

12. In a metallic partition structure, the combination of panel units having framing members of generally channel form with 120
parallel flanges and integral grooves on their web portions, said panel units being assembled with the parallel flanges in opposed spaced alignment to form a hollow vertical, means to secure said aligned flanges 125
together, said means frictionally engaging said aligned flanges and permitting access to the hollow interior, and resiliently secured means covering over said last named means. 130

13. In a metallic partition structure, the combination of panel units having framing members of generally channel form with parallel flanges, said panel units being assembled with the parallel flanges in opposed spaced alignment to form a hollow vertical, means for securing said flanges, said means frictionally engaging the flanges and permitting access to the hollow interior, and 5 means in association with said flange-securing means for resiliently holding post caps.

14. In a metallic partition structure, the combination of panel units each presenting two parallel sheet metal margins assembled 15 with such margins in opposed spaced alignment to form a hollow vertical, a clamping member frictionally engaging one side of such margins, another clamping member engaging the opposite side, post cap engaging 20 means on at least one of said clamping members, and post caps resiliently held thereto.

15. In a metallic partition structure, the combination of panel units presenting sheet metal margins, said panel units being assembled 25 with said margins in opposed spaced alignment to form vertical, spaced clip members for clamping such margins, a screw threaded member fastened clear of said margins and holding said clips, and 30 post caps engaging over said clips by resiliency.

16. In a metallic partition structure, the combination of panel units each presenting two parallel sheet metal margins assembled 35 with such margins in opposed spaced alignment to form a hollow vertical, a clamping member frictionally engaging one side of such margins, another clamping member frictionally engaging an opposite side, a 40 screw threaded member passing clear of said margins and joining said clamping members, and post caps engaging over said clamping members by resiliency.

17. In a metallic partition structure, the 45 combination of panel units presenting parallel sheet metal margins assembled with the margins in opposed spaced alignment to form a hollow vertical, a post cap clip frictionally engaging the exterior of said margins, a clamping member engaging the interior, a screw threaded member passing clear of such margins and joining said clip and clamping member, a post cap resiliently held to said post cap clip, and a floor-attached member for positioning such panel 55 unit assembly.

18. In partition construction, the combination of two panel frames having end members of generally channel form with outstanding flanges, positioned with such flanges in spaced alignment, and another panel frame having a channel vertical angularly positioned with respect thereto, the 60 web portions of all said verticals being 65 equally spaced from a common vertical cen-

ter line, means for securing the spaced apart verticals in position, and means overlapping the juncture of contiguous verticals.

19. In partition construction the combination of two panel frames having end members of generally channel form with outstanding flanges, positioned with such flanges in spaced alignment, and another panel frame having a channel vertical angularly positioned with respect thereto, the 70 web portions of all said verticals being equally spaced from a common vertical center line, means for securing the spaced apart verticals in position, means overlapping the juncture of contiguous verticals, and means 75 overlapping the space between the aligned flanges, such means being resiliently secured in position.

20. In partition construction, the combination of two panel frames having end members of generally channel form with outstanding flanges, positioned with such flanges in spaced alignment, and another panel frame having a channel vertical angularly positioned with respect thereto, the 80 web portions of all said verticals being equally spaced from a common vertical center line, means for securing the spaced apart verticals in position, and means overlapping the space between the aligned flanges, such means being resiliently secured 85 in position.

21. In partition construction, the combination of two panel frames having end members of generally channel form with outstanding flanges, positioned with such flanges in spaced alignment, and another panel frame having a channel vertical angularly positioned with respect thereto, the 90 web portions of all said verticals being equally spaced from a common vertical center line, grooves in the web portions of each of said verticals, and means for securing all 95 said verticals in position.

Signed by me this 2nd day of September, 110
1927.

JOHN A. BOHNSACK.
